SMITH H. COCHRAN AND WILLIAM E. CLOW, OF CHICAGO, ILLINOIS.

REVERSING MECHANISM.

1,169,774.

Specification of Letters Patent.

Patented Feb. 1, 1916.

Application filed March 26, 1915. Serial No. 17,288.

To all whom it may concern:

Be it known that we, SMITH H. COCHRAN and WILLIAM E. CLOW, citizens of the United States, and residents of Chicago, in the county of Cook and State of Illinois, have invented certain new and useful Improvements in Reversing Mechanism, of which the following is a specification.

Our invention relates to a novel reversing mechanism particularly adapted for use in reversing the movements of a washing machine cylinder.

As is well known, it is desirable to provide means for automatically reversing the direction of rotation of certain mechanical elements after a predetermined number of revolutions in either direction. This is particularly true in the operation of certain types of washing machines. In such devices the cylinder or drum is usually rotated in one direction for a short time, then automatically reversed and rotated in the opposite direction. A device which will accomplish this result without the possibility of becoming out of order or being subject to excessive wear is desirable. Such a device is disclosed herein.

The essential features of this application are comprised in a driven element provided with a spiral groove on one face thereof, a drive shaft disposed across the face of said driven element and a clutch, the clutch being operated to engage alternately certain intermediate gears located on opposite sides of the driven element, the clutch being shifted by coöperation with stops located in the spiral groove and acting as the terminals of such groove.

The invention may be more readily understood by reference to the accompanying drawings, wherein—

Figure 1 is a side elevation of a reversing mechanism constructed in accordance with our invention, and Fig. 2 is a section on the line 2—2 Fig. 1.

Referring more particularly to the drawings it will be seen that within a box or casing 10 is mounted a bevel gear 11 having in this instance an integral stub shaft 12 which may engage the drum or cylinder of a washing machine or any other device which is adapted to rotate alternately in opposite directions. The gear 11 is provided with gear teeth 13 at its marginal edge. Within the body of the gear and regularly disposed on the face thereof is a spiral groove 14.

Disposed in each turn of the groove and arranged in the present instance in a radial line are threaded recesses 15, within which screws 16, 17 may be placed. These screws 60 act as stops and define the operative length or extent of the spiral. Coöoperating with this groove is a pin 18 carried by a block 19 slidably mounted on a lever 20, which lever is pivoted at 21 to the casing 10 and 65 has a complementary member 22 riveted thereto, the parts 20 and 22 forming a yoke which enters a circumferential recess formed in a sleeve 23. This sleeve is splined to a drive shaft 24 and is provided with a 70 clutch 25, 26 on opposite ends thereof. The yoke member and the sleeve are adapted to be held in either of their two positions by means of a coil spring 27 connected to the member 22 and to the casing 10 and placed 75 under comparison. The member 20 projects through the casing 10 as shown at 28 and acts as a handle by means of which the clutch may be manually operated. Beveled pinions 29—30 are loosely mounted on the 80 drive shaft 24, these pinions engaging on diametrically opposite sides with gear teeth 13 of the member 11.

It will be seen that when the sleeve has clutched the pinion 30, as shown in Fig. 1, 85 the large gear 11 will be rotated in one direction. However, when the clutch is thrown to engage the pinion 29 the gear 11 will be rotated in the opposite direction although the drive shaft 24 rotates in the same 90 direction in each case. The sleeve or clutch member is automatically actuated in the following manner: After determining the number of revolutions of the driven member which are desired the screws 16, 17 are 95 located in the respective grooves. In the setting shown in Fig. 1 the driven member would be given five revolutions when the pin 18 would strike one of the screws and throw the clutch out of engagement with one pinion and into engagement with the other, whereupon the direction of rotation would be reversed and the pin would travel backward in the spiral groove for five complete revolutions when the opposite screw would 100 be contacted and the machine again reversed.

It will be seen that this construction is so simple that parts could not easily become out of order and very little wear is occasioned. This is particularly true for the reason that the entire mechanism may be 110

inclosed within the casing 10, said casing filled with grease and a cover, 31 applied thereto. Obviously the construction is capable of considerable modification and such 5 modifications as are within the scope of our claims we consider within the spirit of our invention.

We claim:

1. In a reversing mechanism, the combination of a rotatable disk provided with a spiral guide way on one face thereof, a clutch member fixed with relation to the rotation of said disk, said clutch member being adapted to coöperate with said guide-way and to be moved across the face thereof, oppositely rotating power transmission means and means actuated by said clutch member for alternately connecting said power transmission means to a source of power, substantially as described.
2. In a reversing mechanism, the combination of a rotatable element provided with a spiral guide-way thereon, means for adjusting the operative length of said guide-way, a shaft extending across the face of said rotatable element and provided with gears on opposite sides of the axis of rotation of said rotatable element, a clutch and means operative in the spiral guide-way for shifting said clutch and connecting said shaft to said rotatable element by means of either of said gears, substantially as described.
3. In a reversing mechanism, the combination of a gear having a spiral groove in one face thereof, a shaft extending across the face of said gear, pinions loosely mount-

ed on said shaft and engaging said gear, a clutch member splined to said shaft and movable to alternately engage said pinions, and means for shifting said clutch, said shifting means including a pin slideable in said groove, substantially as described.

4. In a reversing mechanism, the combination of a driven member provided with a spiral groove, means for adjusting the operative length of said groove, a driving member, power transmission means between said driving and driven members, said power transmission means being located on 50 diametrically opposite sides of said driven member, a clutch for alternately connecting one of said power transmission means to said driven member, and means operative in said groove for actuating said clutch, substantially as described.

5. In a reversing mechanism, the combination of a gear having a symmetrical spiral groove on one face thereof, stops constituting the ends of said groove, a shaft disposed across the face of said gear, pinions loosely mounted on said shaft and engaging opposite sides of said gear, a clutch member splined to said shaft and adapted to alternately engage said pinions, a lever for actuating said clutch, said lever being provided with a pin entering said groove and by contact with said stops cause the shifting of said clutch, substantially as described.
